UNITED STATES PATENT OFFICE

IVAR T. WEDIN, OF FLINT, MICHIGAN, ASSIGNOR TO A C SPARK PLUG COMPANY, OF FLINT, MICHIGAN, A COMPANY OF MICHIGAN

THERMOSTAT

Application filed December 31, 1928. Serial No. 329,330.

This invention relates to automatically operated devices and particularly to an improvement in valves that govern fluid flow in accordance with temperature of the fluid.

While the field of usefulness of the invention is not limited, it will be found to be particularly adaptable for use in connection with the cooling system of an internal combustion engine, wherein water or other cooling liquid after taking up heat in the engine jacket or water chamber flows through a radiator or condenser where it gives up its heat and then returns to the water chamber. It will be understood that when the engine is first started, 15 the engine and all the liquid in the cooling system is cold and maximum efficiency is not obtained until after the engine has had time to warm up. Obviously, if the circulation of the cooling liquid is cut off or restricted the 20 engine and the water in the engine jackets will heat up quickly to afford maximum operating efficiency in a short time, since the heat is not being carried away by the liquid and dispelled in the radiator.

25 It is an object of the present invention to provide a device which may be inserted in the engine cooling system, preferably between the outlet from the engine and the inlet to the radiator, and which embodied a valve that is 30 automatically operated by and directly dependent upon temperature of the liquid in the cooling system to control the flow therethrough.

Another object of the invention is to provide 35 an improved type of thermostatically operated valve unit which is of simple construction so as to promote ease and economy of manufacture and which will be positive in action and unlikely to get out of order, and 40 which furthermore may be readily installed either as standard equipment on new engines or as an accessory on existing engines.

A further object of the invention is to provide 45 a unit wherein a bi-metallic spring strap of substantially U-shape is employed to hold the valve closed and to open the valve as it expands under temperature increase, and to provide an improved and simple means for adjusting the parts and setting the tension of 50 the spring loop prior to the introduction of

the unit in the system, so that the valve will be operated at a desired predetermined temperature, and will require no further attention thereafter.

Other objects and advantages will be apparent from the following specification, when taken with the accompanying drawing illustrating a preferred embodiment of the invention, and wherein Fig. 1 is a longitudinal sectional view of the temperature control 55 valve unit; Fig. 2 is an end elevation of the unit and Fig. 3 is a transverse sectional view taken on line 3—3 of Fig. 1.

In the drawing the reference character 1 indicates a butterfly or plate valve having in the 60 center thereof a depressed cup-shaped portion 2, the side walls of which are provided at opposite points with outwardly pressed bosses or teats 3 that are journaled in openings in the ends of a pair of forwardly projecting arms 4 on a carrier or frame 5. The frame 5, which in the present instance, 65 comprises parallel side portions and arcuate end portions, is mounted in a cylindrical housing or casing 6 preferably formed from seam- 70 less tubing. The frame 5 is held in place by pressing outwardly projecting bosses 7 in adjacent surfaces of the arcuate end portions of the frame and the wall of the tube 6, thereby 75 eliminating rivet and bolt openings and the 80 possibility of leakage of liquid flowing through the passageway provided by the casing or tubing 6.

A bi-metallic thermo-sensitive spring element 8 of substantially U-shape has one end 85 reversely bent as at 9 and fixedly secured as by soldering, welding or the like to the frame 5, and has its other end projecting through an opening in the portion 2 and curled over to form an eye 10 through which projects a 90 pivot pin 11 having its opposite ends projecting into depressions or openings such as would be formed by outwardly pressed bosses 12 in the side wall of the cup 2. The opening through which the end of the thermo-sensitive element 8 projects, serves also to provide a bleed or leak hole past the valve 1.

When the water surrounding the element 8 is cold, the tension of the spring loop holds the valve in closed position to prevent the 100

flow of the liquid through the unit. Upon increase in temperature, the tendency for the loop will be to expand or enlarge with the result that the valve 1 will be swung about its pivot to a substantially horizontal position 5 so as to allow liquid flow.

An important feature of the present invention is the provision of a stop or abutment finger 13 which may be formed integral with the frame 5, and which contacts with one side 10 of the loop 8 to hold it under predetermined tension. By bending the finger or tongue 13 to and fro, the size of the loop and its tension may be varied and, therefore, the amount of 15 tension that the heat must take up before the valve will open may be controlled. After the parts are completely assembled, the tongue 13 is bent forwardly or rearwardly to secure the desired degree of spring tension so that 20 the valve will operate at a predetermined temperature condition. That is, a forward or rearward movement of the tongue varies the tension, and the action of the heat will open the valve sooner or later as the case may be.

While the invention has been described more or less specifically, it is to be understood that it is not limited to the exact details shown, but that such modifications may be made as come within the scope of appended claims.

I claim:

1. A device of the character described, including a tubular housing adapted for insertion within a fluid passageway, a frame in said housing, interlocking portions on the 35 frame and housing pressed one into the other to hold the parts in assembled relation, a pair of forwardly projecting arms integral with said frame and having apertures adjacent their ends, a butterfly valve having a depressed portion located between said arms 40 and whose side walls are provided with outstanding teats that extend into said apertures to afford a pivotal mounting for the valve, a pivot pin having its opposite ends extending into depressions in the side walls of said 45 depressed portion of the valve, a bi-metallic thermo-sensitive spring strap of U-shape having one end curled around said pivot pin and its opposite end secured to said frame, adapted to swing said valve about its pivot to 50 control fluid flow through the passageway by its expansion and contraction under temperature changes of the fluid, and a stop finger for the spring strap carried by said frame and adjustable for varying the tension of said strap to 55 control the opening of the valve in accordance with predetermined temperatures.

2. A device of the character described including, a tubular housing adapted for insertion in a liquid passageway, a valve in said passageway to control the liquid flow therethrough, a thermo-sensitive element governing the operation of said valve in accordance with liquid temperature, a sheet metal frame 65 pivotally supporting said valve and carrying

the thermo-sensitive element, and means to hold the frame carrying the valve and thermo-sensitive element in said housing, consisting of bosses pressed out of the sheet metal frame into depressions in the housing.

3. A device of the character described, including a tubular housing adapted for insertion in a fluid passageway, a frame carried by and within said housing having forwardly projecting arms, a plate valve having a depressed central portion provided with projections in its side walls extending into openings in said arms to pivotally support said valve and a thermo-sensitive element carried by the frame and connected with the valve to swing the valve and control fluid flow through the passageway in accordance with fluid temperature.

4. A device of the character described, including a housing adapted for insertion in a fluid passageway, a frame secured within said housing, a butterfly valve for controlling fluid flow through the housing and having a depressed portion provided with projections in its side walls that extend into bearings in the frame and by means of which the valve is pivotally supported, and a thermo-sensitive element carried by the frame and operatively connected with the valve to control the position of the valve according to temperature 90 conditions of the fluid.

5. A device of the character described, including a housing adapted for insertion in a fluid passageway, a butterfly valve controlling fluid flow, a thermo-sensitive spring element operatively connected with the valve to automatically control the valve according to the temperature of the fluid, a frame secured in said housing and pivotally supporting said valve and carrying said thermo-sensitive spring, and an integral tongue on the frame forming an abutment for the thermo-sensitive spring and being adjustable to govern the operation of the valve at predetermined fluid temperatures.

6. A device of the character described, including a housing forming a part of a fluid passageway, a valve governing fluid flow through the passageway, a support in the housing on which the valve is pivoted, a U-shaped thermo-sensitive element having one end connected with the valve and the other end secured to said support whereby the valve is automatically swung about its pivot with the expansion and contraction of the thermo-sensitive element upon temperature changes, and an adjustable abutment for an intermediate portion of said element adapted to control valve operation at predetermined fluid temperature.

7. A device of the character described, including a housing forming a part of a fluid passageway, a valve governing fluid flow through the passageway, a support in the housing on which the valve is pivoted, a U-

shaped thermo-sensitive spring connected at opposite ends with the valve and the support to automatically operate the valve in accordance with variations in fluid temperature, and an integral tongue on the support for abutment with the spring, said tongue being adjustable to vary the tension of the spring and thereby govern operation of the valve at predetermined fluid temperature.

8. In a device of the character described, a support, a valve pivoted on the support, a thermo-sensitive element comprising a U-shaped spring having opposite ends connected with the valve and said support, and an abutment for contact with an intermediate portion of said spring carried on said support, and movable to vary the tension of said spring, whereby adjustment may be made to effect operation of the valve at predetermined temperatures.

9. In a device of the character described, a support, a valve pivoted on the support, a thermo-sensitive element having a spring loop therein and connected at opposite ends with the valve and the support to automatically operate the valve upon temperature changes and an abutment on the support for an intermediate portion of said element, which is movable to vary the size of said loop and thereby govern valve operation in accordance with predetermined temperature changes.

10. In a device of the character described, a valve, a thermo-sensitive element having a spring loop therein, which varies in size with temperature changes, and having one end fixed and the opposite end connected with the valve to automatically control the valve in accordance with temperature conditions, and means associated with an intermediate portion of the loop to initially set the size and tension of the loop to effect operation of the valve at a predetermined temperature.

In testimony whereof I affix my signature.
